JOSEPH SLEIVIS, OF CHELSEA, MASSACHUSETTS.

COMBINATION LOCK.

1,418,681.

Specification of Letters Patent. Patented June 6, 1922.

Application filed July 6, 1921. Serial No. 482,673.

To all whom it may concern:

Be it known that I, JOSEPH SLEIVIS, citizen of Lithuania, and resident of Chelsea, in the county of Middlesex and State of Massachusetts, have invented new and useful Improvements in Combination Locks, of which the following is a specification.

This invention relates to lock mechanisms and more particularly to that type of lock in which the movement of the locking bolt is controlled by tumblers actuated by means of indexed knobs or dials and usually known as combination locks.

Locks most commonly employed on the doors of dwelling houses, stores, factories, etc., are of that type necessitating the use of a key for retracting the locking bolt. The many advantages incident to the use of combination locks, that is to say, locks of that type in which the retraction of the bolt is controlled by the manipulation of knobs or dials forming a permanent part of the lock mechanism, are obvious, but to be acceptable for use on an ordinary door, such for example as the street door of a house, such a combination lock must necessarily be of compact form and preferably of such dimensions from front to rear as to permit of the concealing of a substantial portion of the mechanism within the thickness of the door. It should also be so constructed as to prevent its bodily removal or the dismantling of the same from a point outside the door, while at the same time it should be so designed as not appreciably to detract from the appearance of the door.

A combination lock intended for use upon an ordinary door should also be so constructed as to permit of the ready opening of the door from the inside of the same without reference to the position of the locking bolt or the setting of the combination and should also preferably comprise a spring latch of the usual type retractable by means of a knob at either side of the door.

For ease and rapidity of operation the locking bolt should be of the spring actuated type and should be furnished with a manually releasable catch for retaining it in a retracted position. As attempts are sometimes made to force locks by the application of a wrench or other tool to the knob whereby the bolt is retracted, it is desirable to so arrange the parts as to prevent any possible damage thereto by the application

of undue force to the actuating knob when the mechanism is in locking position. Furthermore, a combination lock intended for ordinary use should be of simple construction while at the same time affording the desired protection against surreptitious opening of the door secured thereby and in some cases it may be desirable, in addition to the ordinary tumblers, to provide a separately actuatable latch or latches which must first be manipulated to permit opening of the door, even though the combination be properly set therefor.

In most locks of the class to which this invention relates, the resetting of the combination requires a considerable degree of skill as well as loss of time. Occasions arise, however, for resetting the combination quickly and without resorting to the help of a skilled locksmith for such purpose, and it thus becomes desirable to so design a combination lock as to permit it quickly to be reset by the user and that such resetting may be accomplished merely by turning the dials or indexed knobs to the desired combination at any time when the door is unlocked.

The object of the present invention is to provide a lock mechanism having the various desirable characteristics above enumerated. As exemplifying the several ways in which such object may be accomplished, one embodiment of means well adapted therefor, is illustrated in the accompanying drawings, in which,—

Fig. 1 is an elevation of the lock mechanism as applied to a door and showing the outer side of the same;

Fig. 2 is a longitudinal vertical cross section through the lock mechanism as viewed from the inner side of the door;

Fig. 3 is a vertical transverse cross section through the lock mechanism on a line such as *a—b* of Fig. 2;

Fig. 4 is a transverse vertical cross section on the line *c—d* of Fig. 2;

Fig. 5 is a transverse vertical cross section on the line *e—f* of Fig. 2;

Fig. 6 is a fragmentary longitudinal cross section on the line *g—h* of Fig. 2;

Fig. 7 is a transverse cross section of one of the tumbler devices employed on a line such as *m—n* of Fig. 9;

Fig. 8 is an elevation of the inner end of the actuating knob for one of the tumblers;

Fig. 9 is a side elevation of the knob of Fig. 8; and

Fig. 10 is a fragmentary elevation of the right-hand end of the bolt actuating member.

Referring to the drawings the numeral 1 indicates a door which may be of wood or other suitable material and of a thickness such as is commonly employed for street doors 10 of houses, factories and the like. This door may be provided with a recess in its outside surface for the reception of the lock mechanism. This mechanism is enclosed in a casting comprising a plate 2, having the outer 15 standing flange 3 which overlaps the edge of the door. This member 3 may be provided with openings if desired through which may pass wood screws for attaching the same to the door. The plate 2, upon its 20 inner surface, is provided with a plurality of outstanding bosses 4, 5, which are internally screw threaded for the reception of the ends of attaching bolts or screws 4^a, 5^a.

The operative mechanism of the lock is 25 mounted upon the plate 2, and for enclosing such mechanism, a cover plate 6 is provided, such plate having a rim 7, the edge of which rests against the inner surface of the plate 2. This cover member 6 is furnished with openings for the passage of attaching bolts or screws as 6^a which engage threaded openings in the plate 2 or in parts fixed thereto. The inner surface of the door 30 may be provided with suitable re-enforcing plates for engagement with the heads of the attaching bolts 4^a, 5^a, such bolts passing through the thickness of the door and into the aforesaid bosses 4, 5. As thus secured in 35 position, it is evident that the locking mechanism cannot be removed from the outside of the door without substantially destroying the door itself.

The flange 3 is provided with openings 45 for the passage of the locking bolt 8 and the latch 9, such bolt and latch being guided for reciprocation upon the inner surface of the plate 2. The latch 9 is provided with a beveled face in the usual manner and comprises a tail portion 10 slidable within an opening 50 11 in a block 12 upstanding from the inner surface of the plate 2. Such block 12 may be integral with the plate if desired and may be continuous throughout a considerable portion of the marginal surface of said plate. Within the bore 11 is seated a coil 55 spring 12^a which bears against the rear end of the tail 10 and thus normally tends to project the latch 9. For limiting such movement a transverse pin 13 is secured in the 60 latch, such pin engaging the inner face of the member 3 and thus determining the extent of outward projection of the latch. The latch member is provided with a series of rack teeth 14 along one edge and with such 65 teeth engages a pinion 15. The pinion 15 is

secured to a shaft 16 which extends through the plates 2 and 6 and is provided upon its outer or front end with a knob 17. The shaft 16 also extends through the thickness of the door and through a suitable escutcheon plate 18 secured to the inner surface of the door. This plate may also, if desired, have openings for the passage of two or more of the bolts 4, 5. A knob 19 70 may be secured to said shaft upon the interior of the door. By turning of either of the knobs 17 or 19, it is evident that the latch 9 may be retracted in opposition to the spring 12. An additional guiding block 20 may 75 also be provided if desired.

The bolt 8 is, in general, of the same construction as the latch 9, such bolt comprising a tail 21 guided within the bore 22 in the block 12 and bearing against a spring 23 seated within said bore, such spring tending 80 normally to project the locking bolt 8. The bolt 8 may, if desired, also be guided by engagement with the block 30 projecting outwardly from the plate 2. The bolt is provided with rack teeth at 24 which engage a pinion 25 carried upon a shaft 26. The shaft 26 has bearings at 27, 28, in the cover member 6 and the plate 2 respectively, and upon the inner end of said shaft is mounted a knob 29. By means of the knob 90 29 the bolt 8 may be retracted against action of the spring 23 from the inside of the door, thus permitting the opening of the door from the inside.

Extending outwardly from the bolt 8 is 100 a pin 31, such pin lying to the rear of an arm 32 which projects laterally from the actuator member or bar 33. This actuator member rests against the inner surface of the plate 2 and is guided at its outer end by 105 engagement with a block 34. At its opposite end the actuator bar is provided with a transversely extending enlargement or head 35, from which extend three parallel rods 36, 37, 38. These rods pass through guide 110 openings in a suitable block 39 which is secured to the inner surface of the plate 2, the actuator bar thus being guided for reciprocation in a path parallel to that of the bolt 8. The member 33 is furnished with rack 115 teeth 40 on one edge which engages a pinion 41 carried by a shaft 42. The shaft 42 has bearings at 43, 44, respectively, in the plate 2 and in the cover member 6 and extends forwardly beyond the plate 2. Upon the 120 forward end of this shaft is secured an actuating knob 45. By manipulation of the knob 45 the pinion 41 may be rotated and thus reciprocating motion may be imparted to the actuator bar 33. As this bar is moved 125 to the left as viewed in Fig. 2, the element 32 thereof contacts with the pin 31 of the bolt 8 and thus serves to retract the latter, it being evident however, that such bolt is free to be retracted by manipulation of the 130

knob 29 without reference to the movement of the member 33, as the pin 31 may move freely away from the part 32.

Three rotary tumblers indicated at 46, 47, 5 and 48 respectively, are provided, such tumblers corresponding to the rods 36, 37 and 38, respectively, and serving to determine the retraction of the actuator 33. As indicated in Figs. 7 and 9, each of the tumblers comprises a substantially cylindrical portion 49 provided with a series of openings or depressions such as 50, spaced about its periphery. These openings may be arranged close together or as far apart as may be found desirable. One of these openings, as 51, is of substantial depth and of cylindrical form, such opening preferably extending beyond the axis of the cylindrical portion of the tumbler and being directed radially inward. 20 The other openings or depressions 50 are shallow and preferably of conical form. Each of the tumblers is provided with an axially projecting boss as 52, 53, at its opposite ends, such bosses engaging suitable openings in the member 6 and in the plate 2 respectively, and if desired, the boss 52 may also be provided with an axial opening 54 (Fig. 3) for the reception of a boss or pin 55 extending outwardly from the plate 6 and 25 serving to center such boss. The tumblers as thus positioned between the plates may be freely rotated, the bosses 52, 53, serving as journals therefor. The several tumblers are arranged in triangular formation, that is to say, their axes define the angles of a triangle of substantially equilateral form and the several bars 36, 37 and 38 are arranged to intersect such axes. When the tumblers are properly positioned with their openings 30 51 directed toward their respective bars 36, 37, 38, the ends of such bars are permitted to enter the openings and thus the actuator bar 33 is free to be retracted, carrying with it the bolt 8. When, however, one or more of 35 the tumblers is so turned as to carry its opening 51 out of alignment with the corresponding bar, such bar is unable to enter the same and thus retraction of the actuator 33 is prevented. The shallow openings 50 40 make it difficult to pick the lock by listening to the click of the tumblers as they are rotated past the ends of the bars, the noise produced by the engagement of the end of a bar with one of the openings 50 being substantially the same as that produced by its 45 engagement with the opening 51.

From the forward end of each of the tumblers projects a stem 56, such stem being provided with a circumferential groove 57 (Fig. 3). The several tumblers 46, 47 and 48 are provided respectively with actuating knobs or dials 46^a, 47^a, 48^a. These knobs each comprise a head portion such as 58, see Fig. 3, which may be peripherally knurled 55 if desired for engagement by the fingers of the operator. It also comprises a cylindrical body portion 59 of a diameter substantially equal to that of the main portion of the tumbler. If desired, there may be secured to the inner face of the portion 59 a 70 hardened wear plate 60. This plate may be secured thereto by means of screws 61, see Fig. 8, and is preferably provided with a plurality of spaced openings or sockets 62. While it is preferred to provide a wear 75 plate as just indicated, this is not essential as such openings might be formed directly in the substance of the member 59. The wear plate however, permits the main body of the knob to be made of softer material 80 than is required for the wearing surface thereof.

Through the cylindrical portion of the knob, there is formed a radial opening within which is seated a short pin such as 63, the end of said pin engaging the groove 57. For holding the pin 63 in position the outer end of the opening may be screw threaded for the reception of a set screw 64. The pin 63 serves to prevent removal of the 90 knob 58 from the stem 56 while allowing relative rotary movement of such parts. The body portion of each tumbler is provided with an opening 65 (Fig. 7) parallel to the axis thereof, and in which is slidably mounted a short pin or rod 66 (Fig. 3), such pin at its outer extremity being rounded and at its other extremity engaging a coil spring 67 seated within the bottom of the opening 65. The rounded end of this pin engages one of the sockets or openings 62 in the plate 60 and constitutes a friction clutch for normally securing the knob and the tumbler together but permitting relative movement of such parts when sufficient force is applied to the knob while the tumbler is held against rotation. If desired, a plate 68 may be applied to the front surface of the plate 2 at that point at which the knobs 46^a, 47^a, and 48^a are located in 100 order to provide a longer journal opening for the rotating parts. The body portion 59 of each knob may, as indicated in Fig. 9, be provided with graduations and suitable indicia for indicating its angular position, and cooperating with such graduations the front surface of the plate 68 may be provided with one or more marks or graduations such as 69. With this arrangement, the proper combination for opening the lock 105 is obtained by observing the angular positions of the several graduated knobs or dials when the lock bolt is retracted and the bars 36, 37, 38 are seated within the openings 31 of the several tumblers.

If, while the lock is retracted, it be desired to make up a new combination, it is simply necessary to turn the knobs while the tumblers are held from turning by engagement by the bars 36, etc. If sufficient force 115

be applied to the knobs when the locking mechanism is in this position; they may be turned relatively to the tumblers, the friction clutch device comprising the pin 66 permitting such turning, and the pins 66 slipping from one socket 62 to another. Upon projection of the bolt, the pins 36, etc., are removed from the recesses 51 in the tumblers and thereafter any turning of the knobs results in a corresponding movement of the tumblers, by reason of the engagement of the pins 66 with the openings 62. It is thus impossible to change the combination while the lock bolt is projected and the tumblers may be turned to proper position for opening the lock by setting the several knobs to form the selected combination. By this arrangement it is evident that resetting of the combination may be accomplished at any time when the lock bolt is retracted merely by turning the indexed knobs and observing the new combination thus formed.

For retaining the spring actuated lock bolt in retracted position, the actuator 33 is provided with a plurality of openings such as 69, 70, (Fig. 6) and the plate 2 has secured upon its forward face an outstanding block or boss 71. This boss is provided with a shouldered bore which is continued through the plate 2 and in such bore is seated a coil spring 72. The inner end of such spring rests against the head of a plunger 73 which is engageable with either of the openings 69 or 70, such plunger having a stem 75 passing outwardly through the bore 71 and having a knurled head 74 secured upon its forward extremity. In retracting the lock bolt after setting the proper combination the operator pulls forward on the head 74 thus removing the plunger 73 from the opening 69 and as the bolt is retracted such pin snaps into the opening 70 and retains the actuator 33 against forward projection through the action of the bolt operating spring 23. The bolt may thus be secured in its retracted position and cannot be projected until the plunger 73 has been withdrawn from the opening 70. As additional means for preventing the projection of the bolt, the right-hand end of the actuator as viewed in Fig. 2 and as indicated in detail in Fig. 10 may be bifurcated to form spaced arms 76, 77, respectively, forming a substantially rectangular space therebetween for the reception of a block 78 (Figs. 2 and 5). This block is provided with openings through which pass a pair of guide pins 79, 80, secured in a plate 81 covering an aperture in the member 6. The block 78 is slidable upon the pins 79, 80 and has socket openings in its rear side with which engage coil springs 82, 83, which normally tend to project said block toward the plate 2 and into

the space between the arms 76, 77 of the actuator. The block 78 is provided with a rod 84 which passes out through an opening in the plate 2 and which may be surrounded if desired, by a boss 85 outstanding from the forward surface of said plate. The end of rod 84 serves as a button for the manual manipulation of the block 78 whereby to remove it from between the arms 76, 77 against the action of the springs 82, 83. Thus when it is desired to project the locking bolt 8 it is necessary for the operator to pull outwardly on the member 75 and also to press inwardly on the end of the rod 84 which projects through the front surface of the plate 2.

In order to prevent breaking of the lock parts by the application of a wrench or other tool to the handle 45 or the handle 17, such handles are secured to their shafts in the following manner. Adjacent the end of each shaft, as for example, the shaft 42, there is provided a circumferential slot 85 with which engages the end of a pin 86 retained within a radial opening within the knob by means of a set screw 87. Adjacent the slot 85 the shaft is provided with one or more radial sockets or depressions in its peripheral surface with which may engage a ball 88 seated within a radial opening in the knob and resiliently be forced toward such depression by means of a spring 89. For holding the spring in place a set screw 90 may be employed. With this arrangement, provided there is no substantial opposition to the actuation of the lock mechanism, the ball 88 engaging one of the depressions or sockets in the shaft serves to hold the actuating knob and shaft together to a sufficient extent to permit of the turning of the shaft and the movement of the lock parts. If however, the locking mechanism is not adjusted for movement, force applied to the actuating knob when in sufficient amount, serves merely to turn the knob relatively to the shaft, the ball 88 springing inwardly out of the depression in the shaft and permitting the knob to rotate thereon. The pin 86, however, serves to prevent relative axial movement of the knob and shaft.

If for any reason the setting of the combination in the manner above indicated is found undesirable, the spring pressed pin 66 may be replaced by a pin of a length just sufficient to fill the opening 65 and to engage the socket 62 in the knob. With such an arrangement, upon securing of the knob in position by means of the pin 63 and set screw 64, the knob and tumbler are locked together so that no change of combination is possible, but by removing the knob it may readily be turned to another position causing the pin 66 to engage another of the openings 62 whereupon a new combination 130

will be formed. It is contemplated that this mode of setting the combination may be found advantageous under certain circumstances.

5 Having thus described the invention in a preferred embodiment of the same, together with the mode of use thereof, what I claim and desire to secure by Letters Patent of the United States is:

10 1. A combination lock comprising a slide-
able bolt provided with integral rack teeth,
a pinion engaging said rack teeth, a knob
for rotating said pinion, a pin projecting
from said bolt, a reciprocable actuating bar
15 engageable with said pin, a rod fixedly se-
cured to said bar, a tumbler for engaging
said rod whereby to control the movement
of said bar, rack teeth carried by said bar,
a pinion engaging said rack teeth, and a
20 knob for rotating said pinion.

2. A combination lock comprising a bolt,
and an actuator therefor, a plurality of ro-
tatable tumblers for determining movement
of said actuator in a direction to retract said
25 bolt, said actuator having a plurality of
openings therein, and a manually retractable
spring pressed pin engageable with a se-
lected one of said openings.

3. A lock of the class described comprising
30 a locking bolt, spring means normally tend-
ing to project the same, tumbler-controlled
means for determining retraction of the
bolt, a resiliently actuated part normally
35 tending to prevent projection of said bolt
when the latter is retracted and a manually
movable member connected to said part
whereby to permit of the movement of the
latter to release the bolt.

4. A lock mechanism comprising a recip-
30 rovable bolt, spring means normally tending
to project the same, an actuator for said bolt
comprising a slideable part having a portion
engageable with an element of said bolt, a
block movable in the path of said actuator,
45 spring means tending so to move said block,
and a finger actuatable button having connec-
tions with said block whereby to move the
same out of the path of said actuator.

5. A lock mechanism comprising a lock-
50 ing bolt, a rotatable knob for retracting
said bolt, and connections between said knob
and bolt permitting relative movement of
said knob and bolt upon the application of
sufficient force to said knob.

55 6. A locking mechanism comprising a recip-
rocable bolt, means for moving said bolt
comprising a rack and pinion, a rotatable
shaft upon which said pinion is mounted,
a manually operable knob upon said shaft,
60 and friction clutch means interposed be-
tween said knob and shaft serving normally
to connect the same, but permitting relative
movement thereof upon the application of
sufficient force to the knob.

65 7. A lock mechanism comprising a recip-

rocable part and a rotatable shaft having
connections to said part whereby to cause
movement thereof, a knob mounted upon
said shaft for turning the same, means for
70 preventing relative axial movement of said
knob and shaft, and a ball clutch interposed
between said knob and shaft and serving
normally to connect the same for simul-
taneous rotation.

8. A lock mechanism comprising a recip-
rocable locking member, a shaft for rota-
tably actuating the same, said shaft having
a peripheral groove adjacent one extremity,
and a plurality of circumferentially dis-
80 posed depressions adjacent said groove, a
knob member mounted upon said shaft and
having a pin projecting into said groove
whereby to prevent relative axial movement
of the knob and shaft, a ball seated in a ra-
85 dial bore of said knob, a spring seated in
said bore and normally pressing said ball
inwardly, and an abutment member for re-
taining said spring within the bore, said ball
by engagement with one of said depressions
90 serving normally to secure said knob and
shaft together for simultaneous rotation.

9. A lock mechanism comprising a casing
constructed and arranged to be seated within
the thickness of an ordinary door, a retract-
able locking bolt within said casing, a slid-
95 able actuator for said locking bolt, said actuator
being independent of the bolt and hav-
ing a plurality of rack teeth thereon, a pin-
ion engaging said rack teeth, a knob for
turning said pinion, a plurality of substan-
100 tially parallel rods extending from one end
of said actuator, and a plurality of rotatable
tumblers engageable with the respective rods
and serving to determine the retraction of
said actuator.

10. A lock comprising a bolt, a tumbler,
means controlled thereby for determining
retraction of the bolt, a knob for actuating
said tumbler, means preventing relatively
110 axial movement of the tumbler and knob,
and means permitting the movement of said
knob independently of the tumbler.

11. A lock mechanism comprising a bolt, a
tumbler, means controlled thereby for deter-
mining retraction of the bolt, a manually op-
erable knob for actuating said tumbler,
means preventing relative axial movement
115 of the tumbler and knob, and slip connec-
tions between said tumbler and its actuating
means permitting relative movement of said
parts when the bolt is in retracted position.

12. A lock mechanism comprising a recip-
rocable bolt, a rotary tumbler for determin-
ing retraction of the bolt, said tumbler being
provided with a circumferential groove, a
125 knob for rotating said tumbler, a pin carried
by the knob and projecting into said groove,
and clutch means interposed between said
knob and tumbler.

13. A lock mechanism comprising a bolt, 130

a rotary tumbler for determining retraction of the bolt, a knob for turning said tumbler, means securing said tumbler and knob against relative axial movement, and a 5 spring pressed pin normally operative to connect said knob and tumbler for simultaneous operation.

14. A lock comprising a rotatable tumbler of cylindrical form, a cylindrical knob 10 arranged coaxially with said tumbler and rotatable independently of the same, said knob having a hardened wear plate secured to that end thereof adjacent the tumbler, said plate having a plurality of spaced depressions therein, and a spring projected pin seated in a bore in the tumbler and having a rounded extremity engageable with either of said depressions.

15. A lock mechanism comprising a bolt, 20 tumblers for controlling the retraction thereof, knobs for actuating the respective tum-

blers, said bolt having a transverse opening therein, and a spring pressed pin normally engaging said opening whereby to prevent retraction of the bolt regardless of the position of the tumblers, and means arranged adjacent to said tumblers whereby manually to retract said pin for releasing the bolt.

16. A lock having a tumbler comprising a cylindrical body portion having a radial 30 opening therein, a stem member extending axially from one end of said body portion and having a circumferential groove adjacent its extremity, a knob having an axial bore for the reception of said stem, and a 35 pin mounted in said knob and projecting into said groove whereby to prevent axial separation of the knob and tumbler while permitting relative rotation thereof.

Signed by me at Boston, Massachusetts, 40 this 14th day of June, 1921.

JOSEPH SLEIVIS.
